UNITED STATES PATENT OFFICE.

EZRA B. SMITH, OF RAVENSWOOD, ILLINOIS, ASSIGNOR TO JOHN EDWARD OGDEN,
OF MOUNTAINVILLE, NEW YORK.

ELEVATOR-CAR-CONTROL MECHANISM.

Application filed December 11, 1922. Serial No. 606,278.

To all whom it may concern:

Be it known that I, EZRA B. SMITH, a citizen of the United States, and a resident of Ravenswood, county of Cook, Chicago, and State of Illinois, have invented certain new and useful Improvements in Elevator-Car-Control Mechanism, of which the following is a specification.

This invention relates to doors and particularly to hatchway or fire doors for elevator shafts.

For safety reasons it is very important that hatchway doors be kept closed under normal conditions and when the elevator car is not disposed at the landing opposite the doors. This invention has been particularly developed in connection with the normally closed type of door where the doors at a landing can be opened only when the car is located at that landing.

This invention has for its salient object to insure the closing of hatchway doors before the elevator car leaves the landing where the doors are located.

Another object of the invention is to provide a control mechanism connection between the hatchway doors and elevator car control circuit such that the power will be cut off from the car control circuit when the doors are opened and will be restored only when the doors are closed.

Further objects of the invention will appear from the following description taken in connection with the drawings which form a part of this application and in which—

Fig. 1 is a sectional elevation of an elevator hatchway showing a plurality of sets of hatchway doors.

Fig. 2 is a sectional elevation of one side of the hatchway shown in Fig. 1.

Fig. 3 is an enlarged elevational view of a portion of the hatchway showing the connections between the door control mechanism and the control circuit for the elevator car.

Fig. 4 is a sectional elevation taken substantially on line 4—4 of Fig. 3.

Fig. 5 is a sectional elevation taken substantially on line 5—5 of Fig. 3.

Fig. 6 is a sectional elevation taken substantially on line 6—6 of Fig. 3.

Fig. 7 is an elevational view similar to Fig. 3 but showing another form of connection between the hatchway doors and the car control circuit and

Fig. 8 is a sectional elevation taken substantially on line 8—8 of Fig. 7.

The invention briefly described comprises a switch located in the elevator car control circuit and so constructed and arranged that the power is cut off from the car control circuit when the doors are open and the power is available in the car control circuit only when the doors are disposed in their closed position. In the first embodiment of the invention the door is normally closed, the upper section being heavier than the lower section and in this embodiment a normally closed switch is connected in the car control circuit thereby supplying power to the car. The switch and circuit are opened only when the latch for retaining the hatchway doors open, is disposed in latching position. When this door latch is released allowing the door to close the switch is closed thus restoring power to the car control circuit. The latch releasing operation for the first embodiment is performed by the operator on the car. In the second embodiment referred to the switch in the car control circuit is opened when the doors move to their open position and is closed by the doors when the doors reach their closed position. In some conditions of elevator construction it is desirable to have this circuit closing contact located so the latch at the center of the door will form the contact. In such a case the wires may be extended flexibly from the wall to the center latching device. Further details of the invention will be clear from the following description.

Referring to the drawings, there is shown in Figs. 1 and 2 a portion of an elevator hatchway 10 having a plurality of sets of doors A and B located at different floor levels 12 and 13.

In the particular embodiments of the invention illustrated each set of doors includes an upper section 14 and a lower section 15, these sections being movable toward each other in closed position as shown at B. The latch 16 is carried by one of the sections 14 and is adapted to engage a member 17 on the other section 15. As the doors are moved to closed position the latch 16 is automatically swung into latching position.

The hatchway doors of the second embodiment are preferably so arranged that the upper door sections will be lighter than

the lower door sections whereby when the latch connecting the sections is released permitting the doors to open the lower section will fall by gravity thereby lifting the upper section.

The two doors of each set are connected by a cable 18 secured to the lower edge of the upper section as shown at 19 and to a bracket 20 connected to the lower section 10 adjacent this upper edge. The intermediate portion of the cable passes over a sheave 21 rotatably mounted on a fixed support in the hatchway.

It is desirable that only one pair of doors 15 or door sections be opened at one time and in Fig. 1 the sections B are shown as open and the sections A as closed. It will be obvious that the upper section B will prevent the lower section A from opening and 20 the lower section B will prevent the upper section of the doors located below the landing 13 from opening.

In the form of the invention illustrated in Figs. 1-6 inclusive, mechanism is provided for latching the door sections open. 25 This mechanism is located adjacent the floor levels and the latching mechanism for the doors A adjacent the floor level 12 is shown as disposed in inoperative position 30 and the latching mechanism for the door sections B which are shown as open is illustrated as disposed in operative position. This latter mechanism is shown in detail in Fig. 3 and attention is directed thereto. 35 Each of the latching mechanisms comprises a disc 30 eccentrically pivoted at 31 to a fixed support 32 mounted in the elevator hatchway. The disc 30 has secured thereto an arm 33 to the upper end of which is pivoted at 34 a latching member or pawl 35. 40 The pawl 35 is normally swung in a clockwise direction by a spring 36, its movement being limited by a stop lug 37 formed on the pawl and engaging one edge of the arm 33. The pawl 35 is adapted to engage a 45 bracket 38 secured to the lower door section 15 and the descending movement of this section is limited by a stop 39 secured to the hatchway guide and disposed in the path 50 of the bracket 38.

As above stated the latching mechanism is normally disposed in inoperative position and this is due to the eccentric pivoting of the disc 30 whereby the weight of the 55 disc tends to swing the disc about its pivot 31 to the position shown adjacent the floor level 12 where the arm 33 is inclined at an angle to the vertical. In order to swing the latching mechanism to operative position 60 when the doors are opened each lower section 15 has secured to one edge thereof a resilient strip 40 disposed in position to engage a roller or stud 41 carried by the disc 30. When the lower section approaches 65 its wide open position the strip 40 will en-

gage the roller 41 thereby swinging the disc to the position shown in Fig. 3 wherein the pawl 35 will be engaged by and will snap over the bracket 38 thus retaining the door in open position.

The oscillating movement of the disc 30 about its pivot 31 is positively limited by a stud 42 secured to the hatchway guide and disposed in an arcuate notch 43 formed in the periphery of the disc 30. This stud is 70 headed and the head of the stud serves to retain the disc 30 in position.

In the form of the invention shown in Figs. 1-6 inclusive provision is made for manually releasing the latch 35 from the 80 door when the doors are to be closed. This means includes a bell crank lever 50 pivoted at 51 in the hatchway and having an arm 52 engageable with a stud 53 secured to the arm 33 and illustrated as substantially in 85 alignment with the pivot 34 of the pawl 35. The other arm 54 of the bell crank is connected by a cable 55 to a handle 56, the cable passing over the sheave 57 mounted in the hatchway and the handle being located in a position within the reach of the operator. When the operator pulls on the cable 55 the bell crank will be swung on its pivot thereby swinging the latching mechanism away from the bracket 38 and 90 releasing the doors.

As stated at the outset of the specification it is very desirable that power be cut off from the elevator control circuit when the hatchway doors are open. This is accomplished in the form of the invention shown particularly in Fig. 3, by a flexible connection 60 from the stud 53 to a switch 61 disposed in the elevator car control circuit. This switch includes a pair of spring contact members 62 and 63, these members being normally in contact with each other when the doors are closed and when the latching mechanism is disposed in inoperative position. When, however, the latching arm 33 100 is swung to the vertical position as shown in Fig. 3 the contact member 63 will be drawn out of contact with the member 62 by reason of the flexible connection 60 between the stud 53 carried by the arm 33 and a block 64 connected to the member 63.

The switch 62, 63 and block 64 are enclosed in a casing 65 and the block extends through an opening in the casing and its movement is limited by flanges 64'.

In addition to the manually controlled means for releasing the latch there is provided automatically operable mechanism adapted to release the latch in case of fire causing a dangerous rise of temperature. This means consists of a weight 66 suspended by a chain 67 from a fusible link 68 mounted in the elevator hatchway. A lug 69 carried by the weight is adapted to engage an arm 69' carried by the disc 30 when the 115

weight drops. The vertical movement of the weight is limited by a pin or stud 80 mounted in the hatchway and located in an elongated slot 81 in the weight 66. It will thus be seen that when the link 68 is melted by a dangerous rise in temperature the lug 69 will engage the arm 69' on the disc 30 thereby swinging the latching mechanism away from the bracket 38 and releasing the lower door section. When the latching mechanism is released, the switch 62, 63 will be permitted to close thereby restoring power to the elevator car circuit, allowing the doors to automatically close and permitting the operator to operate the car.

Another embodiment of the invention is illustrated in Figs. 7 and 8 and in this form of the invention no latching mechanism is provided for holding the doors in open position and the car control switch is so mounted as to be engageable by a portion of one of the door sections when the door sections are in their closed position. It will be understood that the doors will remain in open position until they are manually closed because of the fact that the lower door section is made heavier than the upper door section.

Referring to Fig. 7 the upper door section 14 and the lower door section 15 are shown in closed position and the control switch 70 is located opposite a bracket 71 carried by the lower door section. This switch comprises a pair of spring contact members 72 and 73 so constructed that the member 72 tends to spring away from the member 73 and open the circuit controlled thereby. The member 72 has secured thereto a block 74 which is also connected by a strip 75 to the wall of the hatchway and the block 74 is disposed in the path of a wiper 76 carried by the bracket 71 which in turn is mounted, as above stated, on the lower door section. These parts as shown in Fig. 7 are so located that the wiper 76 will engage the block 74 and close the spring contact members 72 and 73 when the lower door section is in closed position. Thus power is available for the operation of the elevator when the doors are closed. When however, the door are open the wiper 76 and the block and contact member 72 will spring away from the contact member 73 thereby opening the circuit.

The switches 61 and 70 may be connected in any suitable manner in the car control circuits. In Fig. 7 the switch is connected in the wire leading to the car control handle 77 and the controller contacts 78 and 79 are connected in the circuit in the usual manner to complete the motor circuit and operate the elevator in the usual manner.

From the foregoing specification it will be seen that simple, practical and effective means has been provided for preventing the

operation of an elevator car when the hatchway doors are open. 65

Although certain specific embodiments of the invention have been particularly shown and described, it will be understood that the invention is capable of further modification 70 and that further changes in the construction and in the arrangement of the various cooperating parts may be made without departing from the spirit or scope of the invention as expressed in the following claims. 75

What I claim is:—

1. In combination, a hatchway door movable to open and closed positions, latching mechanism for latching the door in open position, an elevator control circuit and means controlled by said latching mechanism for opening said circuit when the door is latched and for closing the circuit when the door is unlatched. 80

2. In combination, a hatchway door movable to open and closed positions, latching mechanism therefor, manually operable releasing means for said latching mechanism, an elevator control circuit and means controlled by said latching mechanism for opening said circuit when the door is latched and for closing the circuit when the door is 85 unlatched. 90

3. In combination, a hatchway door movable to open and closed positions, latching mechanism therefor, manually operable releasing means for said latching mechanism, an elevator control circuit and means operatively connected to said latching mechanism for opening said circuit when the door 100 is latched and for closing the circuit when the door is unlatched. 95

4. In combination, a hatchway door movable to open and closed positions, latching mechanism for latching the door in open position, manually operable releasing means for said latching mechanism, an elevator control circuit and means operatively connected to said latching mechanism for opening said circuit when the door is latched 105 and for closing the circuit when the door is unlatched. 110

5. In combination, a hatchway movable to open and closed positions, latching mechanism for holding the door in open position, a car control circuit including a switch mounted in the hatchway and disposed adjacent said latching mechanism, and a flexible connection between said switch and said mechanism whereby said switch will be 115 opened when the door is latched open. 120

6. In combination, a hatchway door movable to open and closed positions, latching mechanism for holding the door in open position, a car control circuit including a switch mounted in the hatchway and disposed adjacent said latching mechanism, a flexible connection between said switch and 125

said mechanism whereby said switch will be opened when the door is latched open.

7. In combination, a hatchway door movable to open and closed positions, latching mechanism for holding the door in open position, a car control circuit including a switch mounted in the hatchway and disposed adjacent said latching mechanism, a flexible connection between said switch and said mechanism whereby said switch will be opened when the door is latched open, manually operable means for releasing said latching mechanism thereby permitting said switch to close, and heat responsive means for releasing said latching mechanism thereby permitting said switch to close.
- 15 8. In combination, a hatchway door movable to open and closed positions, latching mechanism for holding the door in open

position, a car control circuit including a switch mounted in the hatchway and disposed adjacent said latching mechanism, a flexible connection between said switch and said mechanism whereby said switch will be opened when the door is latched open, manually operable means for releasing said latching mechanism thereby permitting said switch to close, and heat responsive means for releasing said latching mechanism thereby permitting said switch to close. 20 25

In witness whereof I have hereunto set my hand this 7th day of Dec., 1922.

EZRA B. SMITH.

Witness:
I. B. MOORE.
